BOTTLE DRAINER

Herbert Pullman, New York, N.Y., assignor to
Fill-A-Mate, Incorporated, New York N.Y.

Filed Oct. 28, 1968, Ser. No. 14,209

Term of patent 14 years

Int. Cl. D6—99

U.S. Cl. D33—3

FIG. 1

FIG. 2

FIG. 3

FIG. 4

FIG. 1 is a top plan view of the bottle drainer;
FIG. 2 is a front elevation thereof;

FIG. 3 is a side elevation thereof; and

FIG. 4 is a perspective view thereof.

The rear elevation is identical to FIG. 2 and the other side elevation is identical to FIG. 3.

The connecting posts in FIGS. 2 and 3 are shown broken away for convenience of illustration.

I claim:

The ornamental design for a bottle drainer, substantially as shown and described.
